UNITED STATES PATENT OFFICE

JOHN FAGG FOSTER, OF DALLAS, TEXAS

MACHINE FOR APPLYING REINFORCING EYELETS TO PAPER

Application filed January 23, 1931. Serial No. 510,476.

This invention relates to a machine for cutting and applying reenforcing eyelets to paper and has particular reference to an apparatus by which paper in web form is reduced into sheets of a predetermined size for commercial use, especially adapted for loose leaf binders where each sheet may be separately inserted or removed from a book or binder wherein means is provided for holding the sheets in position and the principal object of the invention resides in the provision of an inexpensive and wholly practical arrangement of elements cooperating to traverse a web paper over a surface of predetermined extent, perforating the web at spaced predetermined intervals, preparatory to receiving a circular, perforated eyelet of a composition having greater strength and durability than the web to which it is applied.

Still another object of the invention resides in the provision of separate means for perforating the eyelet material, which latter is received and traversed by separate means and placing the said eyelets in a magazine preparatory to their application to the web and whose openings are at all times maintained in register with the perforations made at spaced intervals in the web.

Still another object of the invention resides in means containing a suitable moistening medium which functions to moisten the web at spaced points where the latter is to receive the pre-cut eyelets, it being pointed out that the material from which the eyelets are cut is gummed or otherwise treated so as to firmly adhere to the web when coming in contact therewith.

Yet another object of the invention resides in the provision of means for cutting the sheets into predetermined length as the web emerges from the machine, which it does after a period of time during which the eyelets are allowed to become set, thereby obviating the possibility that they will become displaced.

With the foregoing objects as paramount the invention has particular reference to its salient features of construction and arrangement of parts, which will become manifest as

the description proceeds, taken in connection with the accompanying drawings wherein:

Figure 1 is a diagrammatic side elevation of the preferred embodiment of the invention, the frame having been omitted to better illustrate the operative elements of the combination.

Figure 2 is a fragmentary view, including a side elevation of a thin metal web or belt employed as a medium through which the several elements of the combination are operated.

Figure 3 is a detailed view of one of the plungers constituting the perforating devices, fragmentarily showing the cam operating means and wheel flange, as well as showing in sections the magazine in which is contained the reenforcing eyelet.

Figure 4 is a detailed view of the eyelet punching arrangement as well as the means by which the eyelet material is fed thereunder.

Figure 5 is a reduced perspective view of the punch assembly shown in Figure 4.

Figure 6 is a sectional view on lines 6—6 on Figure 1, and

Figure 7 is a fragmentary view of a sheet of paper on which the eyelet has been applied and showing the completed work of the invention.

Continuing more in detail with the drawings, it may be here mentioned that the elements of the combination are shown diagrammatically, since it is the elements of the combination and not the frame fabrication upon which the claims of the present invention are based. Accordingly the large wheel 1 shown in Figure 1 is mounted for rotation in a suitable frame, and as apparent in Figure 5 particularly, has spaced perforations *a* about its periphery into which extend radially arranged and movable plungers 2. The perforations in the periphery of the flange in the wheel 1 are provided with guide bosses 3 to guide the enlarged ends 4 on the said plungers 2. The enlarged portions 4 on the plungers 2 are reduced at their operative ends at 5 and which reduced portions are of such diameter as to snugly enter the perforations 6 in the metal web or belt 7 which surrounds

the greater portion of the periphery of the wheel 1. This web has affixed thereto, at spaced intervals, transverse reenforcing strips 8 and the perforations 6, previously referred to in the web 7 extend through these reenforcing strips 8, as apparent in Figure 2. Therefore, the portions 5, integral with the enlargements 4 carried by each of the plungers 2 are capable of being projected through 10 the said perforations or apertures 6 during the course of the operation of the machine.

It will be noted in Figure 1 that the belt or web 7 is endless and surrounds rollers 9, 10, 11, and 12, radially situated about the axis 13 of the large wheel 1, although the axis of the rollers 9, 10, 11, and 12 are parallel with the axis of the large wheel 1. In the same figure it will be noted that the large wheel 1 is suspended for rotation upon the axis 13 while a cam 14 is held against rotation by means of the squared bearing 15. It will also be noted that the cam 14 has an inner flange having a gradual rise at b and abrupt drop at c. Reference to Figure 3 will disclose that the inner 20 ends of each of the series of plungers 2 are provided with rollers 16 journaled in U bearings 17, integral with the plunger rods 2. These rollers 16 ride on the machined face of the cam flange and are accordingly actuated 25 thereby since the said cam 14 is stationary while the plungers 2 rotate with the wheel 1. Springs 18 surround the upper ends of the plunger rods 2 and are interposed between enlargements 4 thereon and the inner flange 30 19 of the wheel 1, through which the said plunger rods are slidably longitudinally.

Thus as the wheel 1 rotates, rotation is imparted to the belt 7 by reason of the fact that spaced, semispherical protuberances 20 on the 40 wheel flange are brought into engagement with recesses 21 in the said belt 7 and it being so rotated, the belt 7 imparts rotation to the rollers 9, 10, 11, and 12 by reason of the fact that the reenforcing strips 8 thereon engage within transverse grooves d in the peripheries of the said rollers. Thus rotation of the elements are not wholly dependent upon friction but are positively rotated with 45 coordinative effect, the ratio being predetermined in accordance with the prerequisite spacing of the applied reinforcements, which will be enlarged upon in the course of the description of operation to follow presently.

It being understood that the wheel 1 is 50 the driven element through the medium of the shaft 13, and that the radially spaced rollers previously mentioned are rotated by the belt 7, rotative motion from the upper rollers 9 and 12 is imparted to the moistening 55 roll 22, shown in Figure 1 through the medium of shaft 23, mounted in bearings 24, suitably affixed to the frame of the machine, not shown. A shaft 25 provides for rotation of the cutter roll 26 from the roll 12. The former roll has a series of spaced, transverse-

ly arranged knives 27 which engage the paper web 28 and cut the same into predetermined lengths as the latter emerges from the machine in its completed form. The paper web is normally in the form of a roll of imperforate material, which roll is designated by the character 29 in Figure 1 and is drawn off this roll, between a moistening roll 22 and the guide roll 9 onto the belt 7 and during its course around the wheel 1, is interposed between the inner surface of the belt 7 and the outer periphery of the wheel 1, during which the operation of perforating the paper web and applying the pre-cut reenforcing eyelets 30 is completed, after which the paper web 28 emerges between the cutter roll 26 and the guide roll 12, over the small guide roll 31, all of which are shown in Figure 1.

With reference now to the means by which the reenforcing material is fed, perforated and inserted into the magazines 32, reference is made to Figures 4 and 5, wherein is shown a gear train comprised of gears 33 and 34 and intermediate gear 35, which intermediate gear transmits rotation to gear 33 in a 95 clockwise direction, although the gear 34 is the driven gear, receiving its power of rotation through the medium of shaft 36 and the bevel gear assembly 37. A similar bevel gear assembly 38 is provided at the lower end of the shaft 36 at the axis of the large wheel 1 and through this connection the vertical shaft 36 imparts rotation to the gear 34, while the intermediate gear 35 imparts rotation to the gear 33. Thus, gears 33 and 34 are rotated at the same rate of speed and, as apparent in Figure 5, crank shafts 39 and 40 are provided with cranks 41 and 42 of unequal length carried thereby and pivotally engaged at e to punches 43. It is particularly important to note that the crank 41 is of greater length than the crank 42 and since this is the case, the upper ends of the punch 43 must be slotted to receive the pivots e, in order to provide for the displacement which will occur when the gears 33 and 34 are rotated in the manner explained, to cause reciprocation of the punch 43, such reciprocation being in the form of pitman-like motion, such as shown in dotted lines in Figure 4. It is intended that the replaceable operative ends 45 of the punches 43 impinge the strips of reenforcement material 46 in such a manner that the engagement will be flush when the operative end of the plunger coincides with the magazine 32, which is in fact the apertures a in the periphery of the wheel 1.

Explaining further the function of the eyelet cutting arrangement just described, it is pointed out that the operation of the punch 43 is relatively slower than the movement of the periphery of the wheel 1 and necessarily so in order that the operation of the elements will be properly timed so that one of the eye-

lets 30 will be placed in the magazine 32 preparatory to its being affixed to the web 28 when the magazine reaches such a position as to register with the apertures 6 in the belt 7, which occurs when the magazine passes under the guide roll 9. Moreover, it is pointed out in Figure 4 that the magazine 32, immediately below the guide rolls 47 and 48 is in the approximate position to be engaged by the punch 43, when the latter is in the position shown in dotted lines. The reenforcement material 46 travels slower than the surface of the wheel 1 and is timed with the movements of the punch 43 by the drive afforded through the medium of the shaft 49, having bevel gear connection at one end with the intermediate gear 35 at 50 and at the other end with the guide roll 48 at 51. Thus the reenforcing material and the forming die or punch 43 and its associated elements are operated in coordination with the elements of the combination designed for feeding, moistening and perforating the paper web through the machine.

In operation, the roll of paper at 29 is fed between the moistening roll 22 and the guide roll 9 and the end of the web is turned downwardly to be engaged between the belt 7 and the outer periphery of the wheel 1 which has dual perforations at *a*. It will be noted that the drum 22, situated immediately above the guide roll 9 has spaced valved openings which, during its rotation will engage and moisten the paper web at spaced intervals during its passage between the said drum and the guide roll 9. The thus moistened areas will be so spaced as to coincide with the point where the web is perforated, which occurs directly beneath the roll 9, it being pointed out that the abrupt drop on the cam 14, indicated at *c* causes the rod 2 of the perforated element to be projected radially outward, due to the pressure of spring 18, bringing the projection 5 directly against the paper web, thereby perforating the same and at the same time applying the already perforated reenforcing eyelet 30 against the moistened surface of the paper web. In this connection, it is pointed out that the strips of the reenforcing material 46 are mucilaged and the adhering surfaces are on the upper side of the wheel flange upon which they are guided by means of the guide rolls 47 and 48, the latter being driven through the shaft 49, previously referred to. The reenforcing material being so disposed, the mucilaged surface thereof will be exposed to the paper web, as apparent in Figure 3, wherein the eyelet 30 and the paper web 28 are shown in position just prior to the application of the eyelet to the paper as a result of the abrupt outward projection of the perforating element, occasioned by the dual function of the cam surface at *c* and the pressure of the spring 18.

In Figure 4 it will be noted that the mate-

rial 46 from which the eyelets 30 are formed is fed off the roll 52 and passing between the guide roll 47 and the driven roll 48, the strips of material progress toward the paired punches 43 which latter engage the material and in so doing, the mechanism is so timed that the operative end of the punch 43 will enter the apertures *a* in the periphery of the wheel 1 as the said apertures pass the operative position of the punch. The material thus cut by the downward urge of the punches 43 will remain within the magazine 32 in the form of the eyelet shown in Figure 7 and thus the eyelets will be in position to be urged outwardly against the paper web at the proper time or subsequent to the moistening operation, previously explained.

Particular reference is made to the relationship between the punching process and the moistening and perforating process, it being pointed out that the eyelets 30 are cut and deposited into the recesses or magazines 32 surrounding the projections 5 within the apertures *a* in the wheel 1 just prior to the time the rods 2 of the perforating devices fall off the shoulder *c* in the face of the cam 14, to perforate the paper under the roll 9. The cam 14 has a continuous surface of approximately three-fourths its inner circumference and has a gradual rise, terminating in another continuous surface, terminating in the abrupt drop at *c*. This particular construction allows the enlargement 4 on the rods 2 to bring pressure against the eyelets 30, while the projection 5 carried by the enlargement 4 remains in an extended position through the opening 6 in the belt 7 and reenforcement 8 thereon. Such pressure continues until the wheel 1 has been rotated approximately two-thirds of its circumference, whereupon the gradual rise at *b* on the cam 14 will withdraw the rods 2 and the perforating elements carried thereon, to allow the paper web 28 to pass between rollers 12 and 26 the latter carrying blades 27 which are arranged to cut the paper web into sheets of predetermined lengths.

It is particularly pointed out that the constant pressure applied to the eyelets, to urge them against the paper, combined with the fact that the paper has been moistened at the points where the eyelets are applied, will insure positive adherence of the eyelets to the paper.

The invention has been described with great particularity for the purpose of fully disclosing the relationship and cooperative function of the several elements of the combination but it is understood that it is not intended that the invention shall be limited to any specific details of construction and that certain minor changes and modifications may be resorted to from time to time as fall within the meaning and scope of the appended claims without de-

parting from the spirit and intent of the invention.

What is claimed is:

1. Apparatus for affixing reenforcing eyelets to paper including a rotary element having a series of radially spaced, cam operated perforating devices, guide rolls disposed about said rotary element carrying an endless belt having perforations corresponding to the operative ends of said perforating devices, means to traverse a paper web about said rotary element between said belt and said rotary element whereby to move the same into position to be perforated by said perforating devices, a rotating moistening drum normally in contact with said paper web, a reenforcing eyelet feeding mechanism including means for feeding gummed eyelet material and means for punching said material preparatory to its application to said paper web, means associated with said cam operated perforating devices for retaining said eyelets during their passage from said punching means and means for cutting said web in sheets of predetermined size.
2. Apparatus for forming and affixing gummed reenforcing eyelets to paper including means for traversing a web of said paper in a rotary fashion for discharge combined with means for perforating the paper web at spaced intervals during movement thereof, a rotating moistening drum in contact with said paper web, means for forming reenforcing eyelets from gummed material of greater strength than said paper, preparatory to affixing the same in register with the perforations in said paper web and means associated with said perforating means for retaining the eyelets preparatory to their application to said web.

45

50

55

60

65

3. Apparatus for forming and affixing gummed reenforcing eyelets to paper including means for progressively moving a web of paper combined with means for perforating said paper at spaced intervals, means operative to punch eyelets and arrange the same relative to said perforating means whereby the said eyelets will register with the perforations in said paper web, a rotating drum having spaced openings for moistening said paper web prior to the application of said eyelets, means for retaining said pre-cut eyelets during their passage from said punching means preparatory to their application to said web, and means for applying pressure for a predetermined period of time to allow said eyelets to set.

4. Apparatus for forming and affixing gummed reenforcing eyelets to paper including perforating elements operating at predetermined intervals combined with means for moving a paper web over the operative point of said perforating elements to be perforated at spaced intervals, separate means for punching and arranging said reenforcing eyelets preparatory to their application to said paper in register with the perforations made therein, a guide roll and a moistening drum in contact with said paper for effecting application of said eyelets, means associated with said perforating elements for retaining the pre-cut eyelets during their movement to a predetermined point for application to said web and means for holding said paper and eyelets in contact under pressure to cause said eyelets to become set.
